EXHAUST SILENCER

Lucien L. Haas, Buffalo, N. Y., assignor to Buffalo Pressed Steel Company, Buffalo, N. Y.

Application September 21, 1932, Serial No. 634,179

10 Claims. (Cl. 137—160)

This invention relates to improvements in mufflers or silencers for the exhaust of internal combustion engines.

The objects of this invention are to provide 5 mufflers of improved construction in which the greater part of the exhaust gases can pass directly through the muffler without change in direction of flow; also to provide a muffler of this kind in which the various sound waves present 10 in the exhaust can be reduced to the required extent by means of a series of chambers of improved construction arranged about the central passage through the muffler; also to provide a sound deadening chamber near the discharge 15 end of the muffler with means of improved construction for producing passage of gas therethrough to evaporate liquid discharged into this chamber; also a muffler shell with perforations elongated in the direction of flow of the gases 20 past the perforations to eliminate a whistling or hissing sound; also to improve mufflers of this kind in other respects herein disclosed.

In the accompanying drawings:

Fig. 1 is a longitudinal central sectional elevation of a muffler embodying this invention.

Figs. 2, 3, and 4 are similar longitudinal central sectional elevations of mufflers of modified construction.

Fig. 5 is a transverse sectional elevation of the 30 muffler shown in Fig. 4 on line 5—5, Fig. 4.

Figs. 6, 7, and 8 are longitudinal central sectional elevations of mufflers of modified constructions.

Fig. 9 is a transverse section on an enlarged 35 scale, on line 9—9, Fig. 8.

It has been known for some time that sound waves passing through perforated tubes, if the tube extends through a medium having the property of absorbing sound, will be destroyed or reduced to a sufficient extent so as not to be objectionable. Various sound absorbing materials have been used in connection with mufflers of this kind, but most of these materials have been found unsatisfactory for the reason that the exhaust 45 gases of internal combustion engines contain certain liquid and gaseous materials which cause rapid corrosion of such sound absorbing materials. In accordance with this invention, certain sound deadening chambers containing no sound absorbing material are provided about the perforated central passage or duct through the muffler, in which chambers the various sound waves are absorbed or broken up. Certain gases passing through such chambers are cooled by contact 50 with the outer walls of the muffler and by re-

turning these cooled gases to the main stream of gases flowing through the muffler, a further sound deadening effect is produced.

In the muffler shown in Fig. 1, 9 represents the outer shell of the muffler which is provided at the 5 inlet end thereof with a head 10 and the discharge end with a head 11, all of these parts being of usual construction, the inlet head being provided with the usual tubular extension to which the exhaust pipe from the engine may be 10 connected and the discharge head 11 is provided with a corresponding extension to which the tail pipe may be secured. 12 represents an inner shell of the muffler which is suitably connected with the inlet head, for example, by means of a 15 connecting member 14, one end of which is connected with a shoulder of the inlet head 10 and the other end of which has a telescopic engagement with the adjacent end of the inner shell 12. The inner shell is perforated either throughout 20 the entire length thereof or the greater portion of this shell is perforated, and the perforations may be of any suitable or desired form, but it has been found that if these perforations are in the form of elongated slits 15 extending lengthwise of the direction of flow of the gases through the inner shell, the usual whistling or hissing noise in the inner shell is eliminated, which noise results when perforations of circular and other forms are used.

The discharge end of the inner shell 12 may be supported within the muffler in any suitable manner, and in the construction shown, two baffles 16 and 17 are provided which are arranged in the space between outer and inner shells, and 25 which, therefore, support the inner shell with reference to the outer shell.

The space between the baffle 16 and the inlet head 10 preferably contains one or more intermediate shells, two such shells 18 and 19 being 40 illustrated in the construction shown. Preferably these shells are arranged concentric with the inner shell, and are made tapering or of frusto-conical shape, so that the chambers formed between adjacent shells will be of greater cross sectional area at one end thereof than at the other end, and the gases are preferably caused to flow in these chambers in the direction of their length from the larger toward the smaller end. It has been found that this arrangement has a compressing effect upon the sound waves which results in a very effective deadening of these waves. In the construction shown, the inlet shell 12 is also made of tapering form, having the largest end nearest to the 45 50 55

inlet head of the muffler. This arrangement results in an effect the reverse of that obtained in a megaphone, and furthermore, has the advantage of providing a more restricted passage 5 for the gases at the discharge end of the muffler than at the inlet end, which results in a building up of slight pressure at the inlet end. I utilize this slight pressure to provide a circulation of gas through the chambers formed about 10 the inner shell of the muffler, but it will be understood that this invention is not intended to be limited to mufflers having inner shells tapered in this manner.

Because of the slight pressure built up at the 15 inlet end of the inner shell, it will be obvious that some of the gases at the inlet portion of the inner shell will flow through the perforations or slits 15 into the chamber between the inner shell 12 and the intermediate shell 18, and such 20 gases will flow lengthwise in this chamber and will then pass outwardly through discharge apertures 20 arranged in the end of the shell 18 nearest to the discharge end of the muffler. The 25 gases passing outwardly through the discharge apertures 20 will enter the chamber between the shells 18 and 19 at the larger end of this chamber and will flow toward the smaller end thereof, and then through apertures 21 in the shell 19. These apertures admit the gases into the 30 larger end of a chamber formed between the outer shell 9 and the intermediate shell 19, and the gases will consequently flow lengthwise of this chamber toward the smaller end thereof and through apertures 22 in the baffle 16. In 35 flowing from the larger to the smaller end of a chamber, the sound waves will be subjected to a compressing action which produces a muffling of the same. Preferably, the outer chamber of the series is divided into two parts by means of a transverse baffle 24 arranged between the shells 40 9 and 19 to further reduce sound waves in this chamber.

In the passage through the outer chamber and 45 in contact with the outer shell 9 of the muffler, the gases will be decidedly cooled and these cooled gases are discharged into a chamber formed between the baffles 16 and 17 and the inner and outer shells of the muffler. It will be noted that the portion of the inner shell passing 50 through this chamber is perforated and, consequently, gases are free to pass through these perforations, and also sound waves which have not been absorbed in the portion of the inner shell passing through the intermediate shell 18, 55 will pass through the perforations into the chambers formed between the baffles 16, 17 and head 11 and will be destroyed in these chambers. These two chambers are connected by apertures 25 in the baffle 17.

In the construction shown in Fig. 1, the inner shell 12 terminates short of the discharge passage 26 through the head 11 and the rapid flow of gases from the end of the inner shell toward the discharge 60 26 will set up an ejector action in the cylindrical portion 27 of the head 11, and thus draw into the stream of gas any gases contained in the chamber between the head 11 and baffle 17. This ejector action also stimulates the flow of gas in the two chambers at the discharge 65 end of the muffler and may cause some gases from the inner shell to pass through the perforations of this shell into the chamber between the baffles 16 and 17, and thus mix with the gases discharged from the elongated chambers 70 through the apertures 22 in the baffle 16. The

flowing of the cooler gases crosswise of the hot gases at the discharge end of the inner shell as a result of the ejector action, also has a silencing effect upon the noise of the exhaust. The portion of the tube 12 extending between the baffle 17 and head 11 may, if desired, be made without apertures, in which case this part of the tube will produce an increased suction or vacuum in the chamber between the baffle 17 and the head 11.

The muffler shown in Fig. 2 is quite similar to that shown in Fig. 1. In this construction, the outer shell 30 has heads 31 and 32 at its opposite ends, the head 31 at the inlet end of the muffler having only one shoulder which supports 15 the intermediate shell 33 and a connecting member 34 for the inner perforated shell 35. Only one intermediate shell is used in this construction, which terminates at a transverse baffle 36. A second transverse baffle 37 is spaced between 20 the baffle 36 and the head 32 of the muffler. The cylindrical connection 38 for the tail pipe of the muffler may also be formed as a part of the head 32, and an inwardly extending flange or part 39, which engages the inner shell 35 near 25 the discharge end thereof may also be carried by this head. The discharge end of the inner shell terminates at a distance from the tail pipe connection 38 so that an ejector action is produced by the gases discharged from this inner shell to 30 provide for drawing gases through apertures 40 formed in the inwardly extending flange 39. This induces a flow of gases through the sound absorbing chambers formed between the baffles 36 and 37 and the head 32. The operation of the 35 muffler is substantially the same as the one shown in Fig. 1.

In the construction shown in Fig. 3, the outer shell 43 extends throughout the length of the muffler and its opposite ends are closed by heads 40 44 and 45. This muffler also has a continuous straight passage through the same, and the inner shell or duct in this case is built in a number of sections. The first section 46 of this shell is made substantially cylindrical or without taper, 45 and another section 47 of this shell is made tapering toward the discharge end of this muffler to provide for a material difference in pressure at the two ends thereof, both of these sections being of perforated metal. A short central duct or passage 48 is formed on a baffle 49 which supports the ends of a pair of inner shells 50 and 51, the tube or passage 48 being slightly smaller in diameter than the portion 46 of the inner shell, to provide for a slight difference in 55 pressure tending to cause gases to flow through the chambers formed by the shells 50 and 51. The portion 46 of the inner shell terminates short of the intermediate shell 50 and is spaced therefrom by means of a baffle member 53 having 60 apertures therein, so that some of the gases discharged through the perforations of the part 46 of the inner shell may flow through the apertures in the baffle 53. The portion 46 of the inner shell, therefore, discharges its gases into a 65 chamber formed in the end of the intermediate shell 50 between the baffles 49 and 53, and this portion of the intermediate shell is provided with apertures 54 through which gases and sound waves may pass into the larger end of the 70 tapering chamber between the shells 50 and 51. The shell 51 is provided with discharge apertures 55 through which gases pass into the larger end of the chamber between the intermediate shell 51 and the outer shell 43. The gases pass from 75

the portion of larger cross section to the portion of smaller cross section in both of these chambers and are then discharged through this chamber through apertures 56 formed in the baffle 49. The second part of the muffler is formed between two baffles 60 and 61 which support the portion 47 of the inner shell and also an intermediate shell 62. A space or chamber is formed between the baffles 49 and 60 in which gases 10 discharged through the apertures 56 may flow toward the axis of the muffler to mix with the gases passing directly through the muffler through the passage 48. This flow of cold gases cross-wise of the hot gases produces a further silencing effect on the noise of the exhaust.

A part of the gases discharged through the perforations of the portion 47 of the inner shell pass into the space between this shell and the intermediate shell 62 and flow in this space toward 20 the portion of least cross sectional area and pass out of this space or chamber through apertures 63 formed in the intermediate shell 62. These gases then pass lengthwise of the chamber formed between the intermediate shells 62 and the outer shell 43 and are discharged through apertures 25 64 in the baffle 61 into the smaller end of the space between this baffle and the head 45. The portion 47 of the inner shell terminates adjacent to the head 45 but out of engagement therewith, thus forming an annular passage between 30 this end of the inner shell and the head 45 through which gases may pass through the discharge aperture of the head.

Another form of muffler is shown in Fig. 4, in 35 which an outer shell 70 is provided at opposite ends with heads 71 and 72, and adjacent to the head 71 at the inlet end of the muffler a baffle 73 is provided, spaced from the inlet head 71 and forming a chamber into which the gases may 40 initially pass on entering the muffler. The baffle 73 is provided with an aperture with which a tapering inner shell 74 cooperates to receive gases.

In this construction a tandem arrangement 45 of mufflers is shown, in that another muffler is provided near the discharge end of the outer shell 70, and the gases entering the inlet chamber of the muffler are divided, a part of the gases passing to each muffler. A tube or passage 75 50 terminating at one end in the baffle 73 and at its other end in a baffle 76 conducts gas from the inlet chamber of the muffler to the second muffler. 77 represents an intermediate shell of the first muffler and is secured at one end to the baffle 73 and at the other end to a baffle 78. The shell 77 is provided with gas discharge apertures 79, and the other discharge apertures 80 55 are provided in the baffle 78. The baffle 78 is spaced from a baffle 81 forming between these 60 two baffles a chamber 82 into which gases enter from the apertures 80. The gas from this chamber enters the inner shell 74 through apertures 83 formed in a straight portion of this shell at the chamber 82, and the remainder of this shell 65 is in the form of an imperforate tube and passes through the second muffler and terminates in a baffle 85 near the discharge end of the muffler, so that the portion of the gas entering the inner shell 74 receives all of its muffling in the front 70 part of the muffler, and is then conducted into a discharge chamber 86 formed between the baffle 85 and the head 72, from where it passes into the tail pipe (not shown).

The portion of the gases which pass through 75 the pipe or duct 75 and are silenced in the rear

part of the muffler pass into a chamber between the baffle 76 and a baffle 87 and then enter into a perforated inner shell 88. Most of the gases pass through this shell directly into the discharge chamber 86. Some of the gases pass 5 through the perforations of this shell into a chamber between this shell and an intermediate shell 89, and thence through apertures 90 in this intermediate shell into a chamber between this shell and the outer shell 70. From this chamber, 10 the gases discharge through apertures 91 in the baffle 85 and pass into the discharge chamber 86 of the muffler.

In the case of this muffler, the portion of the outer shell 70 between the baffles 81 and 76 may 15 be omitted, in which case the two mufflers will be separate and will be connected only by imperforate portions of the passages 74 and 75.

The muffler shown in Fig. 6 is provided with an inner shell 95 which tapers toward the inlet end 20 of the muffler, the taper being in the reverse direction of the inner shells described in connection with the Figs. 1 to 4. Otherwise, the muffler is of substantially the same construction as the muffler shown in Fig. 2. Even in the construction 25 shown, there is sufficient difference in pressure at the two ends of the inlet shell 95 to cause a certain percentage of the gases to flow through the several chambers formed by the intermediate shell 96 and by the several baffles 97 and 98 and the 30 heads of the muffler. The action of the chambers about the perforate inner shell on sound waves are substantially the same as in connection with the other constructions described, so that a very effective muffling results.

The construction shown in Fig. 7 is somewhat like that shown in Fig. 2, except that the baffle 100 of this muffler is imperforate, so that any gases passing through the perforations of the inner shell 101 into the chamber between this shell 40 and the intermediate shell 102 will pass through apertures 103 into the chamber between the shell 102 and the outer shell 104, and from this chamber the gases pass back to the intermediate chamber through apertures 105, and thence through 45 the perforations of the inner shell to mix with the gases flowing through the inner shell.

At the discharge end of this muffler, a sound deadening chamber is provided between the baffle 100 and the head 106 of the muffler, and an extension 107 of the inner shell, which extension, however, is imperforate and arranged in this chamber and held in place therein by means of a baffle 108 in such a manner as to leave an annular space between the discharge end of the portion 101 of the 50 inner shell and the portion 107 thereof. A similar annular passage is formed at the discharge end of the part 107 of the inner shell, thus forming an ejector action at this end of the shell which draws gas through the sound deadening 55 chamber between the baffles 100 and 106, the baffle 108 being provided with apertures 109 for the passage of such gases. The annular passages for the gases and the chamber 110 have a decided sound absorbing effect in this muffler, and furthermore, the passage of gases through the chamber at the discharge end of the muffler serves the further purpose of evaporating any liquid which might condense and collect in the chamber 110 of the muffler and at the same time produce cross 60 currents of cool gases at the discharge end of the part 107 of the inner shell, thus further increasing the muffling effect.

In the construction shown in Figs. 8 and 9, a muffler is shown which is built in two parts or 75

sections, as are the mufflers shown in Figs. 3 and 4. In Fig. 8, a single inner shell or tube 115 is provided which probably tapers from the inlet end of the muffler to the discharge end thereof. The inner shell 115 is perforated near the inlet end thereof and the perforated portion is enclosed by an intermediate shell 116 about which is arranged an outer shell 117, heads 118 and 119 being provided at the ends of the outer shell. An annular spacing member 120 is secured to the intermediate shell 116 and forms a support for the inlet end of the inner shell 115. The intermediate shell 116 may be of uniform diameter throughout its length since the tapered shell 115 forms with the intermediate shell a chamber which decreases in cross sectional area toward the inlet portion of the muffler and apertures 121 in the intermediate shell permit the gases to pass into the chamber between this shell and the outer shell. A baffle 122 supports the discharge end of the intermediate shell from the outer shell and this baffle is provided with apertures 123 through which gases may pass into a space or chamber 124 between the baffle 122 and the head 119. In this chamber, the sound waves are compressed to deaden the sound. A further sound deadening chamber 125 is preferably provided between the inner and intermediate shells and between the baffle 122 and a baffle 126 positioned between the intermediate and inner shells. Apertures 127 in the baffle 122 establish a communication between the two sound deadening chambers 124 and 125, so that gases may pass from the former to the latter chamber and then through the apertures in the inner shell which face the chamber 125. By the provision of these different chambers, different sound waves are effectively destroyed.

The second portion of the muffler is somewhat similar to the first portion except that in this case a baffle 129 supports the rear end portion of the inner shell 115. The arrangement of the shells and baffles is such as to form chambers 130 and 131 corresponding substantially to chambers 124 and 125 which have already been described, except that in this case gases are withdrawn from the chamber 131 by the ejector action of the discharge end of the inner shell 115 which is spaced from a cylindrical portion 132 of a baffle 133, so that the discharge of gas from the inner shell will tend to draw gas out of the chamber 131, which in turn causes gas to flow from the chamber 130 to the chamber 131, and consequently also induces a flow of gas in the cylindrical chambers arranged about the inner and intermediate shells. In all of the constructions described, the perforations in the inner shell have the property of breaking up the sound waves by permitting parts of these sound waves to pass into the several chambers formed about the perforated portions of the inner shell. It has been found that longitudinal passages between the inner, intermediate and outer shells have the property of absorbing and deadening a certain type of species of sound waves while other chambers formed between transverse baffles have a similar effect upon other types of sound waves. By the combination of these chambers as described, a very effective muffling of the sound waves is produced with very little back pressure, since most of the gases, of course, flow directly through the inner shell from the inlet to the discharge of the muffler.

I claim as my invention:

1. A muffler having a direct passage therethrough from the inlet to the discharge end thereof through which exhaust gases may flow

without change of direction, said passage including an inner shell provided substantially throughout the length thereof with perforations and tapered toward its outlet end, an outer shell, and an intermediate shell arranged between said inner and outer shells, a pair of transverse baffles between said inner and outer shells, two of said shells forming between them and with one of said baffles a tapering chamber, means for causing gases passing outwardly through the apertures of said passage to flow in said chamber from the larger to the smaller end thereof, and means for returning gases passed through said chamber to said passage at a point further along that passage, said pair of transverse baffles between said inner and outer shells forming with the inner and outer shells a chamber surrounding a perforated portion of said inner shell, and means for conducting gas to said last mentioned chamber from the smaller end of said tapering chamber. 20

2. A muffler having a direct passage therethrough from the inlet to the discharge end thereof through which exhaust gases may flow without change of direction, said passage including an inner shell provided substantially throughout the length thereof with perforations, an outer shell, and an intermediate shell arranged between said inner and outer shells and of less length than said outer shell, heads closing the space between said inner and outer shells, and a baffle located between the head at the discharge end of said muffler and the end of said intermediate shell and forming with said inner and outer shells a chamber for gases, apertures in said intermediate shell to permit gases to flow lengthwise in the chambers formed between said shells, and passages for causing a circulation of gases in said chamber between said baffle and head at the discharge end of the muffler. 30

3. A muffler including an outer shell and heads 40 at the inlet and discharge ends of said shell, said muffler having an inner shell forming a direct passage substantially therethrough from the inlet to the discharge head thereof, through which passage exhaust gases may flow without change 45 of direction, said passage having a portion adjacent the discharge end of lesser cross-sectional area than the opposite end a baffle arranged intermediate of said heads and connecting said inner and outer shells, said inner shell extending through said baffle and provided throughout the greater portion of the length thereof with perforations which are elongated in the direction of the flow of gases in said shell, an intermediate shell arranged between said inner and outer shells 50 and between said baffle and one of said heads, said shells forming a series of chambers arranged one within another and surrounding said passage, said intermediate shell having openings 55 solely adjacent one end through which gases discharged through said perforations of said inner shell may flow, and means for producing a circulation of gases in the space between said baffle and the other head of the muffler. 60

4. A muffler having an outer and an inner shell, 65 said inner shell being provided with perforations substantially throughout the length thereof, a pair of baffles between the ends of said shells, and an intermediate shell extending from one of said baffles to one end of said muffler, said inner shell forming at least a part of an unobstructed passage through said muffler, said intermediate shell forming with said one of said baffles and the outer and inner shells, a plurality of chambers arranged about the axis of the muffler in which 70

- gases can flow lengthwise of said muffler at one side of said one baffle, said intermediate shell being apertured only adjacent the inlet end of said muffler to connect said chambers in series and 5 a chamber extending from the inner to the outer shell being formed at the other side of said baffle, said one baffle being apertured to connect the outermost of the first mentioned chambers to the last mentioned chamber, the other of said 10 baffles being apertured to pass gases, the exit end of said passage having a Venturi section connected to the chamber section between the said other baffle and the adjacent end of said outer shell.
- 15 5. A muffler comprising an elongated, imperforate casing, a tube passing from end to end thereof and forming a direct, free passage therethrough, which in cross-sectional area is smaller adjacent its outlet end than at its inlet end, and 20 then expanded, an elongated shell surrounding and extending in a direction endwise of said tube and within said casing, said shell being tapered with its smaller end adjacent the inlet end of said casing and forming with the tube and casing two telescopic, but oppositely tapered, approximately annular chambers, said tube being apertured at a plurality of intervals along its length, and said shell being apertured solely adjacent its smaller end, and the smaller end of the outer 25 30 chamber being connected to said tube at the expanded zone of the tube, whereby the expanding gases leaving the smaller area of the tube will create a suction in said outer chamber and draw gases through said chambers in succession.
- 35 6. A muffler having an outer and an inner shell, said inner shell being provided with perforations at intervals along the length thereof, said inner shell being substantially straight from end to end but having its cross-sectional area in a section 40 adjacent its outlet end smaller than at the section adjacent the inlet end, and with the ends of the outer shell forming a continuous passage through the muffler, said passage beyond said smaller section of the inner shell having a portion larger 45 than said smaller section a baffle between the ends of said shells, and an intermediate shell extending from said baffle to one end of said muffler, said intermediate shell forming with the inner and outer shells, concentric chambers arranged about the axis of the muffler in which 50 gases can flow in a direction lengthwise of said muffler at one side of said baffle, said intermediate shell being apertured only adjacent the inlet end of said muffler to connect said chambers in series, 55 the space between the inner and outer shells and disposed between said baffle and the other end of the muffler, constituting another chamber, said baffle being apertured to connect the outermost of the first mentioned chambers to the last mentioned chamber, and said last mentioned chamber communicating directly with said passage at the larger section of said passage beyond that section of said passage having said smaller cross-sectional area of the inner shell.
- 60 65 7. A muffler comprising a tubular casing with a header at each end, and with an opening through each header, the opening at the inlet end of the casing having a greater cross-sectional area than the opening at the outlet end, and the opening 70 at the outlet end of the casing being flanged to provide an outlet passage, a tapered tube having a direct passage from end to end, its larger end connected to the inlet header of said casing and communicating with the opening therein, with 75 the tube extending along the interior of and generally spaced from said casing and terminating at its smaller end in proximity to the opening in the outlet header, the outlet header forming with the small end of the tube and with the outlet passage a relatively short chamber of greater cross-sectional area than the adjacent portions of said tube and of said outlet passage, a baffle extending transversely across the interior of said casing approximately between said tube and said casing, an intermediate shell disposed in said casing and 10 around said tube, largely spaced from both tube and casing, and connected at one end to said baffle and at its other end to the inlet header, said tube having apertures arranged along its length, said intermediate shell being apertured 15 adjacent the inlet header and imperforate for the remainder of its length, and said baffle being apertured in the portion between said intermediate shell and casing and being imperforate between said intermediate shell and said tube, and 20 the chamber between said casing and tube at the side of said baffle opposite from said intermediate shell having communication with said expansion chamber at the outlet end of said tube.
- 25 8. In a muffler, a tubular casing having an inlet header at one end and an outlet header at the other end, each header having an opening therethrough, a tube extending through said casing substantially between said headers and open from end to end, said tube having apertures therein 30 at intervals along the same from end to end, the tube with the headers forming a direct passage through said casing, the inlet header and adjacent end of said tube together forming a relatively short passage section having a substantial- 35 40 45 50 55 60 65 70 75 80 85 90 95 100 105 110 115 120 125 130 135 ly spaced from the peripheries of the casing and tube and extending from one of said headers to the nearest baffle, said shell being apertured solely adjacent said one of the headers and said 5 nearest baffle being apertured solely between said shell and casing, the other baffle being also apertured, whereby a portion of the gases passing through said apertures in the tube may pass in series through the chambers formed by the said 10 tube, shell and casing, and then return to the tube, and another portion may return directly to said tube from the chamber between said shell and tube.

10. In a muffler, a tubular casing having an inlet header at one end and an outlet header at the other end, each header having an opening therethrough, a tube extending through said casing and forming with the header a gas passage, open directly from end to end, said tube having 15 apertures therein at intervals along the same in an endwise direction, said passage at the inlet end having a relatively short section of materially greater cross-sectional area than the adjacent sections of the passage, whereby the gases 20 entering said tube through the inlet header will be caused to eddy by the section of greater cross-sectional area and thus caused to impinge to a greater extent against the wall of the tube and pass to a greater extent through said apertures, a baffle disposed across the casing inter- 25

mediate of its ends and through which the tube closely passes, a shell within and spaced from the casing and surrounding and spaced from the tube and connecting the inlet header with said baffle, said shell being apertured adjacent the 5 inlet header and imperforate for the remainder of the length thereof, said baffle being apertured between the shell and the casing and imperforate in the space between the shell and tube, said passage at the outlet end having a relatively short section of greater cross-sectional area than the adjacent portion of the tube and the outlet opening in the outlet header, whereby the gases about to leave said passage will expand in said last named section of greater cross-sectional area, said passage being apertured at said last mentioned section of greater cross-sectional area to provide communication, with that section of the passage, of the chamber between said casing and tube and the baffle and outlet header, whereby the suction in the expansion chamber at the outlet end will draw gases from the chamber between the outlet header and the baffle, and induce movement of some of the gases in series through the chambers formed by the tube and shell and by the shell and casing, in the section between the baffle and inlet header, and thence pass through the chamber between the baffle and outlet header. 10 15 20 25
